UNITED STATES PATENT OFFICE

2,547,341

VAPORIZING-TYPE OIL BURNER

Charles D. Nicholson, Stillwater, Minn., assignor
of one-half to Arthur A. Skauge, Austin, Minn.

Application September 9, 1948, Serial No. 48,467

4 Claims. (Cl. 158—91)

1

The present invention relates to new and useful improvements in oil burners and more particularly to a burner designed for attaching in a position at the outside of a furnace to protect a flame into the combustion chamber of the furnace by way of the fire door or other opening therein.

An important object of the invention is to provide an oil burner including a combustion chamber which may be easily and quickly attached to the outside of a furnace without necessitating any changes or alterations in the construction thereof.

A still further object is to provide an oil burner of a simple and practical construction, which is efficient and reliable in its operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a longitudinal sectional view taken on a line 2—2 of Figure 1;

Figure 3 is a transverse sectional view taken on a line 3—3 of Figure 4; and

Figure 4 is a longitudinal sectional view taken on a line 4—4 of Figure 3.

Referring now to the drawing in detail wherein for the purpose of illustration I have disclosed a preferred embodiment of the invention the numeral 5 designates a hollow substantially cylindrical body which forms a combustion chamber formed at one end with an attaching flange 6 for attaching in a horizontal position to the outside of a furnace, at the fire door or other opening.

A neck 7 is formed at the end of the body 5 adjacent the flange 6 and which comprises the outlet end of the combustion chamber and a nozzle 8 is secured in the neck by screws or the like 9. The nozzle is formed with a tapered opening 10.

The opposite or rear end of the body 5 is formed with an air inlet opening 11 and an air deflecting or dividing disc 12 is positioned in the body 5 in the path of the air entering the opening 11 and cast or united with the body by means of webs 13 to support the disc 12 transversely in the body and with its side edges spaced from the wall of the combustion chamber. The disc

2

12 is also formed with a central air passage 14. A pair of upper baffles 15 are cast with the top of the body 5 between which is a tapped opening 16 for attaching an ignition plug to the body.

5 A pair of lower baffles 17 and 18 are cast in the lower portion of body 5 immediately beneath the upper baffles 15 and between which is positioned a tapped opening 19 for attaching an oil supply line thereto.

10 10 A vaporizing plate 20 is secured in the body 5 by means of a screw 21 with the front end of the plate resting on the lower baffle 18 and with its opposite or rear end of the plate overlying the oil inlet port 19.

15 15 The rear end of plate 20 is bifurcated to form a pair of spaced parallel arms 22 which are bent upon themselves to clamp the ends of a wicking strip 23 of non-combustible material which is curved downwardly at its center to absorb 20 excess oil when the burner is cold.

An opening 24 is formed in rear lower baffle 17, to permit oil to spread over a larger area in the body 5, when the burner is cold.

In the operation of the burner, a suitable 25 blower (not shown) is attached to air inlet 11 to force air through the burner. The wick 23 is initially ignited by a plug (not shown) attached in opening 16 and the flame passing over plate 20 will heat the plate and vaporize oil 30 collected under the plate. The resultant flame is projected from nozzle 8 into the furnace.

The heating of plate 20 by the flame will cause vaporization of the fuel to produce an efficient combustion.

35 35 A plug 25 is threaded in the top of body 5 to permit use of a screw driver for tightening screw 21 to hold vaporizing plate 20 in a fixed position.

Having described the invention, what is claimed as new is:

40 1. An oil burner comprising a hollow body forming a combustion chamber having an air inlet at one end and an outlet at its opposite end, a nozzle in the outlet, an oil supply port in the bottom of the body, a vaporizer supported 45 in the body above the oil supply port, a starting wick carried by the vaporizer, and an air deflector in the body between the inlet and the vaporizer and obstructing direct passage of air through the body.

50 2. An oil burner comprising a hollow body forming a combustion chamber having an air inlet at one end and an outlet at its opposite end, a nozzle in the outlet, an oil supply port in the bottom of the body, a vaporizer supported 55 in the body above the oil supply port, and an

air deflector in the body between the inlet and the vaporizer and obstructing direct passage of air through the body, said vaporizer comprising a horizontal plate and a starting wick carried at the front end of the plate.

3. An oil burner comprising a hollow body forming a combustion chamber having an air inlet at one end and an outlet at the opposite end, a nozzle in the outlet, an oil supply port in the bottom of the body, an elongated vaporizer supported in the body above the oil supply port, a starting wick at the front portion of the vaporizer and an air deflector in the body between the inlet and the vaporizer and comprising a disk supported in the body opposed to air entering the body and having its edges spaced from the walls of the combustion chamber to obstruct direct passage of air through the body.

4. An oil burner comprising a hollow body forming a combustion chamber having an air inlet at one end and an outlet at its opposite end, a nozzle in the outlet, an oil supply port in the bottom of the body, an air deflector positioned in the combustion chamber immediately rearwardly of the air inlet and in the path of air entering the inlet, an igniter receiving opening in the top of the body, a pair of upper baffles in the body between which the igniter open-

5
10

ing is positioned to pocket oil vapor between the baffles to facilitate starting of the burner, a pair of lower baffles in the body between which the oil supply port is positioned to pocket oil between the lower baffles, a vaporizer plate supported in a horizontal position over the oil supply port and resting on at least one of said lower baffles, and a starting wick at the front portion of said vaporizer plate.
